INCORPORATED, OF WEST ORANGE, NEW JERSEY, A CORPORATION OF NEW JERSEY

ELECTRICAL SOUND RECORDING AND REPRODUCING APPARATUS

Application filed October 13, 1928. Serial No. 312,228.

This invention relates to electrical sound recording and reproducing apparatus and more particularly to a combined unit for electrically recording or reproducing sound 5 for use with phonographs of the dictating machine type.

It is an object of this invention to provide apparatus of the class described which will electrically record and reproduce sound in 10 connection with the "hill and dale" records of the type used on dictating machines with a high degree of quality.

It is a further object of this invention to provide apparatus of the class described in 15 which extraneous noises and distortion in the recording and reproduction is eliminated or reduced to a minimum.

It is a further object of my invention to provide apparatus of the class described which is simple and economical to construct 20 and rugged and reliable in operation.

Still further objects of my invention will be apparent from the specification.

The features of novelty which I believe 25 to be characteristic of my invention are set forth with particularity in the appended claims. My invention itself, however, both as to its fundamental principles and as to its particular embodiments, will best be understood by reference to the specification and accompanying drawing, in which—

Figure 1 is a side elevation of a recorder and reproducer according to my invention, shown in position for recording;

Figure 2 is a similar view of the apparatus shown in position to reproduce;

Figure 3 is a bottom plan view of the apparatus shown in Figures 1 and 2, and

Figure 4 is an exploded perspective view 40 of the recorder frame and reproducer lever assembly.

In accordance with my invention, I provide a frame arranged to be attached to the usual traveling arm or carriage (not shown) 45 of a dictating machine. The frame carries a magnet having pole pieces defining preferably a plurality of air gaps in which there is provided an armature mounted for vibration.

The frame carries below a pair of float-

ing supports preferably arranged one above the other and preferably pivoted about a common axis for vibration in a cylindrical plane. On the upper of the said floating supports there is provided a lever arm pivotally mounted for vibration and carrying at one end a stylus or jewel for engaging the record.

On the lower of the floating supports there is mounted a lever, also pivotally mounted for vibration and carrying also a jewel or stylus for engaging the record. The side levers are selectively engageable with the record, one for recording, the other for reproduction. One of the levers is connected to the vibrating armature. The other lever is normally free but is so arranged that when engaged with the record a vibration-transmitting connection is established by it and the other lever in such a manner that vibrations are transmitted to or from the armature.

Referring now more particularly to the figures, 1 designates a frame or base arranged to be attached to the usual traveling arm or carriage (not shown) of a dictating machine and carrying a magnet support 2, which is preferably in the form of a sheet of metal of sufficient strength having a horizontal flange portion 3, which engages the base 1 and is held thereon, for example, by means of bolts 4 and 5. The flange 3 may be provided with slots to permit of adjusting the position of the magnet. The magnet 6 is provided with a pair of pole pieces 7 and 8, so formed as to provide pole tips 9, 10, 11 and 12. An armature 13 is mounted for vibration between said pole pieces. A coil 14, which may be wound upon a suitable form, is provided surrounding armature 13. If desired, a sheet of conducting material such as copper or the like 15 may be provided over the top of the coil. The armature 13 is preferably cylindrical, except at its upper end, where it may be made relatively thin and flat as at 16 and is extended beyond the air gap for a purpose which will later be described. To provide damping of the armature, a strip of rubber 17 may be

100

positioned between the end of the armature 16 and pole pieces 9 and 11.

The armature is carried by a strip 18, preferably of non-magnetic material such as brass, having ears 19 and 20 bent over the pole pieces. A spring 21, which may for example be phosphor bronze, is secured by means of bolts 23 to the ears 19 and 20, and insulating material such as strips 22 of bakelite are interposed between the ears 19 and 20 and bolts 23, which secure the spring 21 in position. The lower end of the armature may have a shoulder formed thereon so that it may be secured in the spring by passing a collar 24 around the projecting end of the armature. The lower end of the armature projecting below the collar may then be upset as at 25, thereby securing the armature in position. The pole pieces may be laminated and secured together in any suitable manner, as, for example by rivets 71, and the entire magnet assembly may be secured to the member 2, as, for example, by means of bolts 70, as sufficient clearance is preferably allowed to permit of adjusting the magnet assembly on the member 2.

The base 1 is provided on its under-side with a layer of insulating material, such as fibre 32, below which there is mounted a ring frame 27 carrying arms 34 and 35, which form the support for the floating recorder and reproducer assemblies. The recorder assembly 28 preferably comprises a frame 31, provided with arms 36 and 37, reinforced by a cross brace and bolt 50. The open ends of said arms are pivoted as at 36^a and 37^a to permit the carrier frame 31 to have a certain amount of movement in a vertical plane. The carrier frame 31 is provided with means for mounting the recorder arm. This may be in the form of downwardly extending ears 39 and 40, carrying bearing screws 41 and 42, which screws may be provided with tapered inner ends to engage tapered depressions in arms 43 and 44, secured to the recorder arm 30. The free end of the recorder arm 30 is provided with a stylus or jewel 45 for engaging and engraving the record; the other end 46 is pivotally connected to link 26, which, in turn, is pivotally connected at its upper end to block 47, secured in the end of armature 13. The recorder assembly 28 may be provided with a block 53, serving to increase the weight of the recorder assembly to the desired value. The reproducer assembly 29 preferably consists of a ring 54 secured to carrier block 55, which is, in turn, pivoted between arms 34 and 35. The ring 54 may be fitted with an inner assembly secured in position by means of screws or bolts not shown and forming an inner ring 56; provided with bearing screws 57 and 58.

The reproducing lever is preferably in the form of a ring 59 and carries, as at point 60, a suitable stylus or jewel. The ring 59 is somewhat smaller in radius than the free end of recording lever 30 and is placed in position with the free end of the recording lever extending through it. The reproducing lever 59 is normally free, that is to say, there is no connection between it and armature 16.

In the operation of the apparatus according to my invention for the purpose of recording sounds upon a record, the recording and reproducing assemblies are both disengaged and allowed to swing downward until the recording stylus 45 engages the surface of the record. Under such conditions, the reproducing support swings downwardly to the full extent of its motion, while the recorder assembly swings downward until the recording stylus makes contact with the record. If speech currents derived from a suitable microphone or other source are now supplied to the coil 14, the armature will be vibrated and the vibrations thereof transmitted through link 26 to the recording lever, and the stylus will engrave the surface of the record in accordance therewith; at the same time, the floating support permits the stylus to follow irregularities in the surface of the record without adversely affecting the recording of sounds therein.

When it is desired to reproduce sounds, the reproducer assembly is permitted to swing downwardly while the recorder assembly 28 is prevented from so doing, as, for example, by the inter-position of dog 51 under tongue 52 of the recorder assembly. The dog 51 is manually operable in a manner well known in the art by means of a pivotally mounted lever (not shown) which may be carried by the usual traveling arm or carriage of the dictating machine so that the dog may be easily brought into or out of engagement with the tongue 52 at the will of the operator. As the reproducer assembly swings downwardly, the portion of ring 59 opposite the reproducer stylus 60 engages the upper side of the free end of the recording lever 30, thereby rotating the ring 59 in counter-clockwise direction until the stylus 60 engages the record. As the record passes under the stylus, it will be raised and lowered in accordance with the vibrations engraved upon the record, and the opposite side of the ring will transmit these vibrations to the recording lever 30, which, in turn, transmits them to armature 13 through link 26. The floating support for the ring 59 permits the axis thereof to rise and fall to eliminate the effect of irregularities in the surface of the record or in the shape of the mandrel on which it is mounted, while at the same time the vibrations

are transmitted to the recording lever and thence to the armature. The vibrations of the armature, as will be understood, vary the flux through the coil and generate currents corresponding closely to the vibrations of the reproducing stylus. Such currents may be converted into sound by the use of a telephone receiver connected to the coil, or, if desired, they may be amplified and supplied to a loud speaker.

10 For the purpose of providing an adjustable stop limiting the downward motion of the reproducer assembly, the screw 61 may be passed through the ring frame 27 between the arms 34 and 35 in such a manner as to be engaged by the upper side of block 55. It will be understood that by varying the position of screw 61 it is possible to control the amount of free movement of the reproducer assembly.

15 While I have shown and described certain preferred embodiments of my invention, it will be understood that modifications and changes may be made without departing from the spirit and scope of my invention, 20 as will be understood by those skilled in the art.

I claim:—

1. An electrical sound recorder and reproducer, comprising, in combination, a frame, a pair of floating supports pivotally mounted on said frame, one over the other, a recording lever mounted on one of said supports for oscillation thereon, a reproducing lever mounted on the other of said supports for oscillation thereon, a magnet mounted on said frame, a pair of pole pieces mounted on said magnet and defining an air gap, an armature biased to neutral position mounted for vibration in said gap, a connection between said armature and one of said levers for transmitting vibrations between said armature and said lever, and means for transmitting vibrations between said levers under predetermined conditions.

2. An electrical sound recorder and reproducer, comprising, in combination, a frame, a pair of floating supports pivotally mounted on said frame, a recording lever mounted on one of said supports for oscillation thereon, a reproducing lever mounted on the other of said supports for oscillation thereon, said levers being alternatively engageable with a record, a magnet mounted on said frame, a pair of pole pieces mounted on said magnet and defining an air gap, an armature mounted for vibration in said gap and biased to neutral position, a connection between said armature and one of said levers for transmitting vibrations therebetween, and means for establishing a vibration-transmitting connection between said levers when desired.

3. An electrical sound recorder and reproducer comprising, in combination,

frame, a recording lever carried by said frame, a reproducing lever carried by said frame, said levers being arranged for selective engagement with a record, a magnet mounted on said frame, pole pieces mounted on said magnet to form an air gap, an armature mounted for vibration in said air gap, and a connection between one of said levers and said armature for transmitting vibrations therebetween, said levers being arranged to establish a vibration-transmitting connection therebetween when desired.

4. An electrical sound recorder and reproducer, comprising, in combination, a frame, a pair of floating supports carried by said frame, a recording lever mounted on one of said supports, a reproducing lever mounted on the other of said supports, said levers being arranged for selective engagement with a record, a magnet mounted on said frame, pole pieces mounted on said magnet to form an air gap, an armature mounted for vibration in said air gap, and a connection between said armature and one of said levers for transmitting vibrations therebetween, said levers being so arranged that when the other of said levers is engaged with said record, a vibration-transmitting connection is established between said levers.

5. An electrical sound recorder and reproducer, comprising, in combination, a frame, a pair of supports carried thereby, a recording lever mounted for vibration on one of said supports and a reproducing lever mounted on the other of said supports, a magnet mounted on said frame and having pole pieces defining an air gap, an armature mounted for vibration in said gap, and a connection between said armature and one of said levers, the other of said levers being normally free and so arranged as to be maintained in vibration-transmitting contact with the first of said levers when said other lever is engaged with said record.

6. An electrical sound recorder and reproducer, comprising, in combination, a frame, a pair of supports carried by said frame, a recording lever mounted on one of said supports for vibration thereon, a reproducing lever mounted on the other of said supports for vibration thereon, a magnet mounted on said frame and having pole pieces defining an air gap, an armature mounted for vibration in said air gap and a connection between said armature and said recording lever, said reproducing lever being normally free and being arranged to be maintained in vibration-transmitting relation with said recording lever when said reproducing lever is engaged with a record.

7. An electrical sound recorder and reproducer, comprising, in combination, a frame, a pair of floating supports carried by said frame, one below the other, a recording lever pivotally mounted on the upper sup-

port for vibration thereon, a reproducing lever pivotally mounted on the lower support for vibration thereon, a magnet mounted on said frame, an armature mounted for vibration in the field of said magnet, and a connection between said armature and said recording lever, said reproducing lever being arranged to be out of contact with said recording lever when said recording lever is in contact with a record and to be in vibration-transmitting contact with said recording lever when said reproducing lever is in contact with a record.

8. An electrical sound recorder and reproducer, comprising, in combination, a frame, a pair of floating supports carried by said frame, one below the other, a recording lever pivotally mounted for vibration on the upper support, a reproducing lever pivotally mounted for vibration on the lower support, said levers being selectively engageable with a record, a magnet mounted on said frame, an armature mounted for vibration in the field of said magnet, and a connection between said armature and said recording lever, said levers being so arranged as to be out of engagement when said recording lever is engaged with a record, and in contact when said reproducing lever is engaged with a record.

9. An electrical sound recorder and reproducer, comprising, in combination, a frame, a pair of floating supports carried by said frame, one below the other, a recording lever pivotally mounted for vibration on the upper support, a reproducing lever pivotally mounted for vibration on the lower support, said reproducing lever having a portion extending above said recording lever, said levers being selectively engageable with a record, a magnet mounted on said frame, an armature mounted for vibration in the field of said magnet, and a connection between said armature and said recording lever, said levers being so arranged that said reproducing lever engages the upper side of said recording lever when said reproducing lever is engaged with a record.

10. An electrical sound recorder and reproducer, comprising, in combination, a frame, a pair of floating supports carried by said frame, one below the other, a recording lever pivotally mounted for vibration on the upper support, a reproducing lever in the form of a ring pivotally mounted for vibration on the lower support and encircling said recording lever, said levers being selectively engageable with a record and having stylus points on opposite sides of their fulcrum, a magnet mounted on said frame, an armature mounted for vibration in the field of said magnet, and a connection between said armature and said recording stylus, said reproducing lever being normally free.

11. An electrical sound recorder and re-

producer, comprising, in combination, a frame, a pair of floating supports carried by said frame, recording and reproducing levers carried by said supports respectively, a magnet, an armature mounted for vibration in the field of said magnet, and with which each of said levers is arranged to have vibration-transmitting connection, and means for establishing and for rendering inoperative at will vibration-transmitting connection between said armature and one of said levers.

This specification signed this 12th day of October, 1928.
